SHINGLE NAIL LOCK

Carroll C. Figge, Chicago, Ill.

Application June 15, 1931, Serial No. 544,553

7 Claims. (Cl. 108—33)

This invention relates in general to a combined nail and lock for shingles and has more particular reference to flexible composition roofing and shingles.

5 One of the principal objects of the invention is in the provision of a shingle holding device in which there is no direct hole for leakage through the shingles.

A further object of the invention is in the provision of a combined nail and lock for shingles in which the perforations through the shingles and into the roof holding board are offset to prevent leakage.

10 15 15 One of the objects of the invention is in the provision of a combination nail and shingle lock which is bent or deformed for driving into the roof deck.

Other objects of the invention will appear hereinafter, a preferred embodiment of the invention being illustrated in the accompanying drawing.

20 20 In the drawing, Figure 1 shows a portion of a roof having composition shingles to which the present invention is applied;

Figure 2 is a sectional view of the combined nail and lock as applied to a shingle and extending into the roof deck;

Figure 3 is a sectional view showing a shingle lock for connecting shingles in adjacent courses without any leakage hole between them;

30 30 Figure 4 is a sectional view of a modified nail lock having a straight base;

Figure 5 is a sectional view of a modified nail lock having an offset base;

Figure 6 is a perspective of a nail lock in accordance with this invention, having an offset base;

35 35 Figure 7 is a plan view of a shingle lock formed of strip material; and

Figure 8 is a section taken on the line 8—8 of Figure 7.

In attaching strip or individual composition 40 shingles to a roof deck it is desirable to prevent the exposed edge or butt from upward movement, but if a fastening nail is inserted directly through the shingle into the roof deck, a direct hole for leakage is provided. With some types of shingles 45 and roofing the fastening nails of one course are covered by the shingles of the course above, but in this type, a separate attaching device is preferably used for holding down the exposed edge or butt of the shingle.

50 50 In the present invention, both of these objections are overcome and the fastening nail and the shingle lock are combined in a single device which not only secures the shingles or roofing to the roof deck but also provides a lock extending 55 through or about the exposed edge of the shingle

and out of line with the fastening portion so that no direct hold is provided through adjacent shingle courses to provide a direct path for leakage.

Referring now more particularly to the drawing, a number of shingle strips 10, 11, and 12 are applied to boards 13 of a roof deck in overlapping relation, and the exposed edges of these strips are usually cut or recessed to form a shingle pattern having exposed butts or tips 14.

60 A combined shingle nail and lock 15 composed of stiff wire or the like, is angularly bent to provide a driving portion 16 which preferably has a slight curve or offset 17 adjacent to the body portion to strengthen it for driving into the roof deck. The other end 18 of the wire is also angularly bent 65 taking the position 18a as indicated in Figure 2, so that in applying the overlying shingle 12 the point of this extremity may be inserted through the lower exposed edge of the shingle and this end 18 of the wire then bent downwardly against the upper face of the shingle, as shown in Figure 2.

70 If desired, a shingle nail lock 20 may have an extremity 21 for insertion through the exposed edge of a shingle 12 with the other extremity 22 partially bent so that it will pass readily through the softer material of the composition shingles but when it engages the boards 13 of the roof deck it will curl upwardly thereby securing the different strips tightly together and preventing their dislocation from each other but not actually securing 75 the shingles to the deck.

80 80 Another form of shingle nail lock 25 is shown by Figure 4 having a pointed extremity 26 adapted to be inserted through the shingle layers into a roof board 13 and having a driving offset 27 at 85 the head of the pointed extremity 26 and with a locking extremity 28 adapted to extend around the lower edge of a shingle 12, and not through it, with a tip 29 bendable downwardly against the surface of the overlying shingle 12 out of direct line or offset with respect to the driving portion 26. A similar nail lock 30, as shown in Figures 5 and 6, has a driving extremity 31 connected to the main body by a lateral extension or offset 32 and with a driving bend at the head of the driving portion and with an overlying extremity 34 having a downwardly turned tip 35. With this construction, the driving end 31, being offset, is easily engaged by a hammer or other means for driving it into the roof deck.

90 90 95 A strip device for accomplishing the same result is shown by Figures 7 and 8, in which a metal strip 36 has oppositely extending pointed tongues 37 and 38 punched out of the strip on opposite sides thereof and of sufficient length so that one 100 105 110

of the tongues may be inserted through one or more layers of composition shingles into a roof deck and the other tongue may be inserted through the exposed edge of an overlying shingle strip and thereafter bent over for attaching and holding the shingle strip in place.

With these combination shingle nail and lock devices, it is obvious that the overlying shingle or shingle strip may be secured in place by inserting a portion of the device through the strip or around the edge of the strip and thereafter clinching the device in engagement with the shingle; neither the portion perforating the overlying shingle nor the extremity of the device is in alignment with the nailing end of the lock so that no direct hole is provided by means of which water may pass through the layers of shingles and into the roof deck. The perforations are offset to prevent leakage and the perforation of the overlying shingle strip or the point of engagement of the shingle nail lock with the surface of this strip is below the point of attachment of the device to the roof deck so that even if water did pass through the outermost shingle it would not run into the hole made by the driving part of the nail lock. It is furthermore obvious that this combined nail lock may be placed at the very tip of a shingle butt or through it, or may extend over the edge of the shingle at an angle thereto, all as shown in Figure 1.

I claim:

1. A wire shingle nail lock having a shingle perforating portion, a nailing portion, and a connecting portion, and the nailing portion having a stiffening crook adjacent but below the top to facilitate driving it without bending.
2. A combined wire nail and shingle lock comprising a continuous round wire stock having a nailing portion at one end having means for stiffening it for driving, a bendable shingle perforating and engaging portion at the other end, and an intermediate connecting portion to offset the other portions so that the engaging portion is not in line with the nailing portion, the stiffening means comprising an offset in the shank of the nailing portion below the top thereof.

3. A combined nail and shingle lock comprising a nailing portion having a stiffening driving offset at the top and in the shank thereof adapted to be inserted through a lower shingle course to attach shingles to a roof deck, a locking portion extending at an angle to the nailing portion and adapted to be inserted through and bent into engagement with the surface of a shingle in a course to cover the upper end of the nailing portion and the locking portion extending out of line with the nailing portion to prevent formation of a continuous hole through adjacent shingle courses.

4. A combined nail and shingle lock formed of continuous round wire stock, the ends being bent one to form a nailing portion having a shank with a top stiffening crook and having barbs therein, and the other to extend through and over the top of a shingle layer in a course above the nailing portion and having an extremity bendable to engage the upper surface of such shingle layer but out of line with the nailing portion below.

5. A shingle nail lock having a nailing portion with a shank having an offset adjacent but below the top for stiffening it for driving, a bendable shingle perforating and locking portion, and an intermediate connecting portion for offsetting the other portions laterally and out of alignment with each other.

6. A wire nail and shingle lock having a barbed nailing portion at one end with a shank having an offset stiffening crook adjacent but below the driving end, a bendable shingle perforating portion with a shingle engaging tip at the other end, and a connecting angular portion to offset the other portions so the tip and nailing portion are not in alignment.

7. In a shingle nail and lock made of continuous bendable round wire stock, an extremity bendable to engage a shingle, an intermediately connecting portion, and a driving extremity at an angle to the connecting portion having an offsetting crook in the shank at its upper end but below said angle adapting this extremity to be driven without easily bending.

CARROLL C. FIGGE.
